UNITED STATES PATENT OFFICE.

JAMES HIRAM COPASS AND ROBERT BRACKENRIDGE PERKINS, OF ALTUS,
OKLAHOMA.

REVOLVING EGG-SUPPORT FOR INCUBATORS.

1,115,285.

Specification of Letters Patent. Patented Oct. 27, 1914.

Application filed November 6, 1913. Serial No. 799,493.

To all whom it may concern:

Be it known that we, JAMES HIRAM COPASS and ROBERT BRACKENRIDGE PERKINS, citizens of the United States, residing at Altus, in the county of Jackson and State of Oklahoma, have invented certain new and useful Improvements in Revolving Egg-Supports for Incubators; and we do declare the following to be a full, clear, and exact description of the invention, such as will enable others skilled in the art to which it appertains to make and use the same.

This invention relates to incubators and more particularly to egg turners therefor and the primary object of the invention is to provide a simple and efficient device of this character which will enable a large number of eggs to be turned at one and the same time without danger of breaking the same. This object is carried out by constructing the egg tray and turner in the manner herein-after more fully described and claimed, and as shown in the drawings wherein—

Figure 1, Sheet 1, is an end elevation of a deep tray or drawer containing a pair of our revolving egg turners. Fig. 2 is a cross section through the same showing the outer half of the uppermost cylinder removed. Fig. 3 is an enlarged cross section through one of the cylinders, showing the construction of its screen wire and strips. Fig. 4 is a vertical section on the line 4—4 of Fig. 2.

The egg turner forming the principal feature of the present invention comprises a rather deep tray (hereinafter called a drawer) 1 having notches 2 in its ends for removably receiving the shafts 3 and 4 of a plurality of drums, each drum in turn carrying a number of cylinders into which the eggs are placed. Each of said shafts at the front end of the drawer is squared as shown, and when a key is applied the entire drum can be rotated for a partial revolution without removing it from the drawer or removing the drawer from place; in fact, the squared extremity might project entirely through the front door of the incubator casting, and the key could be applied thereto without opening said door. We have shown two of said drums mounted side by side in each drawer, but obviously this is not necessary as there could be a greater or lesser number. Each drum is made up of wooden core blocks 5, to the outer faces of which are secured metal heads 6 of polygonal contour

(herein shown as having five straight sides), and the shafts project through said blocks and heads and serve as supports as above described. These heads carry between them and around the core formed by the blocks a number of two-part cylinders 7 of number 16 mesh screen wire, the inner parts or halves of the cylinders being closed at their extremities by the heads and attached thereto, and the outer parts 8 being removable. Along each edge of the inner part is secured a U-shaped guide strip 9, and each edge of the outer part 8 is bent outward and laid over a metal tongue 10, which latter in turn is then folded over onto the edge and the parts soldered together. The tongues thereafter may slip into the slots of the guide strips 9, so that the outer part 8 is rendered removable from the inner part 7. Each end of the outer part is closed as at 11 in any suitable manner, but preferably by wire mesh as indicated. This leaves the outer part or half of the cylinder removably attached to the inner part or half, and the latter carried by and forming part of the drum which is rotatably mounted in the drawer. When now the outer half of any cylinder is withdrawn, the inner half may be filled with eggs as indicated and the outer half slipped back into place, then the drum is rotated for a partial revolution to bring the outer half of the next cylinder into position to be moved longitudinally on the inner half, across the end of the drawer, and this cylinder in turn is filled with eggs. Finally after all cylinders are filled, they balance the drum on its trunnions or pivots, and the revolving egg support may be turned step by step at any time when it is desired to turn the eggs.

We have found by experience that this device eliminates the possibility of breaking the eggs in handling or turning them, and effects considerable saving in the amount of fuel consumed in proportion to the number of eggs.

These egg turners will hold about twice as many eggs as it is possible to place on a floor space equal to the diameter of the cylinders, because obviously several of the cylinders in any drum are supported above the floor space.

In setting an incubator provided with this egg turner, two of the drums are supplied with eggs three days prior to filling the other two, and after the eggs have re-

- mained in the cylinders eighteen days they are taken out and placed in other and preferably shallower trays elsewhere in the incubator and the hatch finished there, the cylinders just emptied being refilled so that continuous incubation may be kept up. In said shallower trays the chicks have ample opportunity to escape from the eggs when they break the shell.
- 10 In the use of the egg turners above described and shown in the drawing any preferred form of heating and ventilating apparatus may be used, and as the same forms no part of this invention a showing and description thereof are entirely omitted from the drawing and specification respectively.
- From the foregoing, it will be seen that we have provided a simple, inexpensive and efficient means for carrying out the objects 20 of the invention and while we have particularly described the elements best adapted to perform the functions set forth, it is obvious that various changes in form, proportion and in the minor details of construction 25 may be resorted to without departing from the spirit or sacrificing any of the principles of the invention.
- What is claimed as new is:
1. The herein described egg turner comprising a drum made up of a core, polygonal heads at the ends of said core, and shafts projecting from the ends of the core through the heads; and a series of two-part foraminous cylinders carried by said core.
  2. The herein described egg turner comprising a drum made up of a core, polygonal heads at the ends of said core, and shafts projecting from the ends of the core through the heads, one end of said shafts being squared; a series of two-part foraminous cylinders carried by said core; and a drawer having notches in the upper edges of its ends for receiving said shafts therein.
  3. The herein described egg turner comprising a drum made up of a core, polygonal heads at the ends of said core, and shafts projecting from the ends of the core through the heads; and a series of two-part foraminous cylinders carried by said core, the inner part of each cylinder being disposed between the heads and having grooved guides along its edges, and the outer part having

its ends closed and tongues along its edges slidably mounted within said guides.

4. The herein described egg turner comprising a drum made up of a core, polygonal heads at the ends of said core, and shafts projecting from the ends of the core through the heads; and a series of two-part foraminous cylinders carried by said core, the inner part being disposed between said heads and having its edges turned outward, U-shaped guide strips secured to said edges and standing beyond the edges of the heads, the outer part having its ends closed and its edges bent outward, and sheet-metal tongues soldered to said outturned edges and slidably mounted within said grooved guides, for the purpose set forth.

5. In a revolving egg support for incubators, the combination with a core, heads carried by the extremities thereof, and means for supporting the core for rotation on its axis; of a series of foraminous cylinders whose inner halves are secured between 75 said heads and whose outer halves are movably connected with their inner halves.

6. In a revolving egg support for incubators, the combination with a core, heads carried by the extremities thereof, and 80 means for supporting the core for rotation on its axis; of a series of foraminous cylinders whose inner halves are secured between said heads and have grooved guides along their edges, and whose outer halves are slidably mounted over the inner halves and have radially projecting tongues along their edges engaging said guides.

7. In an egg support for incubators, a rotatable drum, supporting means therefor, 90 and a series of two-part cylinders carried thereby, the inner sections of said cylinders being disposed substantially within the drum and the outer sections thereof projecting therebeyond.

In testimony whereof we have hereunto set our hands in presence of two subscribing witnesses.

JAMES HIRAM COPASS.

ROBERT BRACKENRIDGE PERKINS.
